UNITED STATES PATENT OFFICE.

ANDREW J. HOUTS, OF ST. LOUIS, MISSOURI.

DESIGN FOR A BOTTLE.

SPECIFICATION forming part of Design No. 19,847, dated May 27, 1890.

Application filed March 12, 1890. Serial No. 343,865. Term of patent 7 years.

To all whom it may concern: .

Be it known that I, ANDREW J. HOUTS, a citizen of the United States, residing at the city of St. Louis, in the State of Missouri, 5 have invented and produced a new and useful Design for a Bottle, of which the following is a specification, reference being had to the accompanying drawings, forming part thereof.

Figure I is an elevation of my newly-designed bottle, and shows its rear side with a circular panel. Fig. II is a horizontal section taken on line II II, Fig. I, and shows the transverse form of the bottle and of its panel on said line; and Fig. III is a horizontal section 15 taken on line III III, Fig. I, and shows the transverse form of the bottle on that line.

The essential feature of my design consists of a broad flat bottle having flat edges, the broad faces being slightly rounded off to meet 20 the flat edges, and one side of the bottle consisting of a plain rounded surface flattened slightly around the center, and the other side a slightly-rounded surface having a circular panel impressed entirely below the general 25 contour of the rounded surface.

Referring to the drawings, 1 represents the front side of the bottle, and 2 its rear side.

3 represents the flat edges that connect the sides, toward which edges said sides slightly curve.

4 is the neck of the bottle, and 5 the bevel edge around the bottom of said bottle. 30

6 represents the convex circular panel in the rear side of the bottle, which is depressed entirely below the general contour of the 35 rounded surface, especially near its periphery, and 7 represents the depressed integral circular frame or bevel incasement around the periphery of said panel.

The front side 1 of the bottle presents a 40 wide, smooth, capacious face.

I claim as my invention—

The design for a bottle, substantially as herein shown and described.

ANDREW J. HOUTS.

In presence of—

BENJN. A. KNIGHT,
SAML. KNIGHT.
